[57] CLAIM

An ornamental design for a paper shredder, as shown and described.

DESCRIPTION

FIG. 1 is a front view of a paper shredder of the present invention;

FIG. 2 is a top view of the paper shredder shown in FIG. 1; FIG. 3 is a left side view of the paper shredder shown in FIG. 1;

FIG. 4 is a right side view of the paper shredder shown in FIG. 1;

FIG. 5 is a bottom view of the paper shredder shown in FIG. 1;

FIG. 6 is a back view of the paper shredder shown in FIG. 1;

FIG. 7 is a front view of the paper shredder shown in FIG. 1 with one support arm extended;

FIG. 8 is a bottom view of the paper shredder shown in FIG. 7; and,

FIG. 9 is a back view of the paper shredder shown in FIG. 7.

The broken line showing of the cord in FIGS. 1, 2 and 7 is for illustrative purposes only and forms no part of the claimed design.
